UNITED STATES PATENT OFFICE.

JOHN NEWBERRY REYNOLDS, OF GREENWICH, CONNECTICUT, ASSIGNOR, BY MESNE ASSIGNMENTS, TO WESTERN ELECTRIC COMPANY, INCORPORATED, A CORPORATION OF NEW YORK.

SELECTOR-SWITCH.

1,168,419.

Specification of Letters Patent. Patented Jan. 18, 1916.

Application filed December 16, 1913. Serial No. 806,992.

To all whom it may concern:

Be it known that I, JOHN NEWBERRY REYNOLDS, a citizen of the United States, residing at Greenwich, in the county of 5 Fairfield and State of Connecticut, have invented a certain new and useful Improvement in Selector-Switches, of which the following is a full, clear, concise, and exact description.

10 This invention relates to improvements in switch mechanism which is adapted to connect any one of one group of lines to any one of another group of lines, and is particularly designed for connecting lines of a 15 group such as subscribers' telephone lines to lines of another group, usually smaller, such as distributing trunk lines.

15 The principal feature of this invention resides in the provision in a switch of this 20 kind of an improved terminal bank structure wherein the terminals of the two groups of lines are mounted in stationary structures entirely independent from each other.

25 In order to facilitate the explanation and understanding of this invention, it will be described as a line switch or trunk finder and as such might be arranged to serve for example a group of one hundred subscribers' lines and a corresponding group of say ten 30 trunk lines. It is of course obvious that in the following description, the terms "incoming lines" and "outgoing lines" might be substituted for lines or subscribers' lines and trunk lines respectively.

35 The apparatus herein disclosed comprises two sets of bars or shafts corresponding respectively to the subscribers' lines and the trunk lines. The bars of the two sets extend at right angles to each other and all the 40 bars of each set are substantially parallel and lie in the same plane. These bars at their adjacent points or points of intersection are provided with coöperating contact operating means, each trunk bar being provided with a rotatable and laterally movable 45 arm, and each line bar with a cam adapted upon its actuation to force a corresponding arm of the trunk bar into engagement with a contact set.

50 The line terminals, which consist of multiply connected flexible strips, are mounted together in one structure and the trunk terminals, which consist of multiply connected contacts, are mounted independently but ad-

jacent to the outer ends of the line terminals. Obviously, the line terminals and trunk terminals could be reversed without in any manner affecting the operation of the switch. The free ends of the line terminals project outwardly in such a position 60 that they may be flexed into engagement with their coöperating trunk contacts by the corresponding contact operating means of a pair of bars upon the successive movement of a bar of each set. In practice some 65 one of the trunk bars or shafts would preferably always be displaced to a position such that the succeeding movement of a line bar would effect interengagement of the terminals of the line with the terminals of the trunk 70 corresponding to the preselected or "set" trunk bar.

Referring now to the drawings—Figure 1 is a perspective view of a switch with parts broken away; and Fig. 2 is a plan view of a set of cooperating contacts and the operating mechanism therefor.

Secured to member 1 and other similar frame members (not shown) is a plurality of bars 2, 3, 4, 5, etc., which form the opposite sides of the switch support. Secured to the supporting member 1, to the rear of the members 2 and 4, is a supporting bar 6 to which is secured one end of the bank of comb-like incoming line terminal strips 7. These terminal strips have the flexible projecting contact teeth or tongues 8 formed integrally therewith; thus all the terminals of a line are multiply connected. The strips 7 are arranged in groups of three with layers 9 of insulating material therebetween and are secured in position by any desirable means such as a clamping bolt 10. Mounted upon the supporting member 4 at the right, and another support corresponding thereto at the left (not shown), is a plurality of supporting strips 11 to which are secured the comb-like trunk terminal strips 12. These terminal strips 12 are also formed with projecting contact teeth 13. The strips 12 are separated from the supporting bar 11 and from each other by the insulating strips 14, and are secured in position in any desired manner, that shown being by means of clamping screws 15.

When the line terminals are released and occupy their normal position, as shown in Fig. 2, the trunk terminals are located im-

mediately to the left thereof but out of engagement therewith, as shown in said figure. The springs of each set of line terminals are insulatively connected by means of the 5 spacing sleeves 16 and the bolt 17. The line contact tooth at the right in each set projects forwardly in a position to be engaged by the contact operating mechanism carried by the bars which intersect adjacent thereto, 10 these being the bars corresponding to the line and trunk represented by the contacts or terminals of the set.

Pivotal secured between the member 5 at the right and a corresponding member at 15 the left, not shown, is a plurality of rotatable shafts or rods 18 one being provided for each trunk line. Rotatably mounted between the member 2 at the top and a corresponding member at the bottom is a plurality of rotatable bars or shafts 19, one of 20 which is provided for each incoming or subscriber's line. These bars or shafts will hereafter be referred to as trunk bars and line bars respectively. Each of the bars 18 is provided with a plurality of arms 20 loosely mounted thereon but normally retained in a fixed position by means of 25 springs 21 which have their outer ends fixed to the shafts 18 and their inner ends loosely positioned between the pins 22 projecting from the arms 20. The outer end of each of the arms 20 is provided with a contact operating member or ball 23 of insulating material. Projecting from each of the bars 30 19, immediately adjacent the long line spring of each set, is a cam member 24 provided with a grooved surface adapted to engage a member 23 as shown in Fig. 2. Secured to each of the rods 18 is an armature 25 and mounted upon the members 4 and 5 in operative relation thereto is an electromagnet 26, the armature 25 being normally held retracted by means of a 35 spring 27. Fixed to each of the line bars 19 is an armature 28 and mounted upon the supporting members 2 and 3 in operative relation to the armature 28 is an electromagnet 29. A spring 30 is provided for maintaining the armature in a retracted 40 position.

Having now described the structure of this switch, its operation is as follows: Through the operation of circuit controlling means, which are not shown and need not 45 be described, some one of the electromagnets 26 will at all times be energized and consequently some one of the trunk bars 18 will at all times be rotated to preselected or set position. This rotation of the trunk bar 50 will place each of the insulating members 23 carried thereby in an operative relation, or, as shown in the drawings, directly to the right of the long line spring of its respective contact set. It will also place the members 23 in a position where they may be

engaged by their respective cam members 24. Now upon the event of an incoming call, the electromagnet 29 corresponding to the calling line will become energized through the operation of appropriate circuit controlling devices, thus rotating the corresponding line bar 19. The grooved cam 24 will thus engage one of the insulating members 23 on the preselected trunk bar 18, rocking the arm 20 sidewise on the bar 75 18 and causing interengagement of the corresponding set of contacts as shown in dotted lines in Fig. 2 of the drawings. The electromagnet 29 corresponding to the incoming line will be retained energized as 80 long as the call exists. The electromagnet 26 corresponding to the actuated trunk bar, however, will be released immediately after the appropriate bar 19 has been rotated and will then return to normal, carrying with 85 it all its contact actuating arms with the exception of the one engaged by the grooved cam 24 of the actuated line bar. Another bar 18, however, representing an idle trunk or outgoing line will now be immediately 90 rotated to set or preselected position. Upon the rotation of the next trunk bar to set position, the insulating member 23 thereof will engage the upper face of the corresponding cam 24 of the actuated line bar 95 and will be held from passing into operative relation to the corresponding contact set by means thereof, the shaft 18 turning freely in the end of the arm 20. Upon the termination of the connection, means will be actuated which will cause the deenergization of the electromagnet 29 and the corresponding bar 19 will then be rotated back to its normal position by its spring 30, thus releasing the contact actuating arm 20 which, under 100 the tension of the spring 27, will be rotated back to normal position in alignment with the other arms on the same trunk bar.

As many modifications might readily be made in this invention without departing 110 from the spirit thereof, it is to be understood that the invention is to be limited merely by the scope of the appended claims.

What I claim is:

1. In a switch, a plurality of series of 115 multiply connected incoming line terminals secured in a stationary bank, a group of contact operating devices, one for each series of terminals, a plurality of multiply connected outgoing line terminals similarly 120 mounted adjacent thereto, a second group of contact operating devices, one for each series of outgoing line terminals, and means whereby the operation of a device of each group will cause engagement of terminals 125 of the corresponding series.

2. In a switch, a plurality of series of multiply connected incoming line terminals secured in a stationary bank, a group of contact operating devices, one for each series of 130

- terminals, a plurality of series of multiply connected outgoing line terminals similarly mounted in a separate stationary bank, a second group of contact operating devices, 5 one for each series of outgoing line terminals, and means whereby the operation of a device of each group in a predetermined order will cause engagement of terminals of the corresponding series.
- 10 3. In a switch, a plurality of series of multiply connected incoming line terminals mounted in a stationary bank, a group of rotatable shafts, one for each of said series of terminals, a plurality of series of multiply connected outgoing line terminals similarly mounted in a separate stationary bank, a second group of rotatable shafts, one for each series of outgoing line terminals, and means whereby the operation of a shaft of 15 each group will cause engagement of terminals of the corresponding series.
- 15 4. In a switch, a terminal support, two groups of stationarily mounted metallic strips, multiply connected contacts projecting therefrom, the strips of one set extending in one direction and the strips of the other set being arranged to extend at substantially right angles to the first group, and means for causing interengagement of 20 the contacts of the two groups.
- 20 5. In a telephone exchange, a group of lines, a plurality of substantially parallel fixed terminal strips for said lines, multiple contacts projecting from each of said strips, a second group of lines, a plurality of terminal strips for said second group of lines mounted in a stationary bank independent of said first mentioned strips, multiple contacts projecting from each strip 25 of said second group, and means for selectively causing engagement of the contacts of the two groups of lines.
- 25 6. In a switch, a plurality of substantially parallel metallic comb-like strips, the teeth of said combs being the multiplied terminals of a group of lines, a second plurality of metallic comb-like strips at substantially right angles to said first mentioned strips, the teeth of said second plurality of strips 30 being the multiplied terminals of a second group of lines, stationary banks in which said strips are mounted, and means for flexing the teeth representing the terminals of any line of one group, whereby they may be 35 caused to engage the contact teeth of a line of the second group.
- 35 7. In a switch, a plurality of metallic terminal strips insulatively mounted in a stationary bank substantially parallel to each other, flexible contact teeth projecting from said strips, a second plurality of insulated metallic terminal strips similarly mounted, contact teeth projecting from said second plurality of strips, and means whereby a 40 contact tooth of any one of said first men-
- tioned plurality of strips may be forced into engagement with a contact tooth of any one of said second plurality of strips.
- 45 8. In a telephone exchange, a group of lines, stationary metallic strips in which said lines terminate, flexible contact teeth projecting from said strips, a second group of lines, a second plurality of stationary metallic terminal strips for said second group of lines, contact teeth projecting from said second plurality of strips respectively adjacent to cooperating teeth of said first mentioned strips, said second strips being mounted independently of and extending at substantially right angles to said first mentioned strips, and means for flexing the teeth of one set of strips, whereby they may be caused to engage the corresponding teeth of the other set of strips.
- 50 9. In a telephone exchange, a group of lines, fixed insulated terminal strips in which said lines terminate, flexible contact teeth projecting from said strips, a second group of lines, fixed insulatively mounted terminal strips in which said second group of lines terminate, contact teeth projecting from said second mentioned strips, two sets of intersecting bars, and means whereby the successive displacement of a bar of each set will cause engagement of terminal teeth of 55 any line of one group with terminal teeth of any line of the other group.
- 55 10. In a telephone exchange, a plurality of substantially parallel terminal strips insulatively mounted in sets in a stationary bank, a plurality of sets of flexible contact teeth projecting from each set of strips, a second plurality of contact strips at right angles to said first mentioned plurality, said second set being also insulatively mounted 60 in sets in a stationary bank, sets of contact teeth projecting from each of said second named sets of terminal strips respectively adjacent to contacts of the first mentioned strips, and means for flexing the contact teeth of the first mentioned sets, whereby they may be caused to engage the adjacent teeth of the last mentioned sets of strips.
- 65 11. In a telephone switch, a plurality of substantially parallel terminal strips insulatively mounted in sets in a stationary bank, a second plurality of terminal strips mounted independently of and at right angles to said first mentioned strips, said second plurality of strips being also arranged 65 in sets, sets of terminal teeth projecting from said first mentioned sets of strips, there being as many sets of teeth for each set of strips as there are sets of said second mentioned strips, sets of terminal teeth projecting from said last mentioned sets of strips adjacent to the contact teeth of the first mentioned strips, there being as many sets of contact teeth for each of the last mentioned strips as there are sets of those 75

first mentioned, and means for flexing the teeth of the first mentioned strips whereby they will be caused to engage the corresponding teeth of the second mentioned strips.

12. In a telephone exchange, a group of lines, sets of terminal strips in which said lines terminate, said strips being fixedly and insulatively mounted parallel to each other in a bank, a second group of lines, sets of terminal strips in which said second group of lines respectively terminate, said second mentioned strips being mounted independently of and extending at substantially right angles to said first mentioned strips, sets of flexible contact teeth projecting from said first mentioned strips, one set for each line of the second group, sets of contact teeth projecting from said second mentioned sets of strips, there being one set of contacts for each line of the first mentioned group, sets of rotatable bars extending adjacent to said contacts, and means whereby the successive rotation of a bar of each set will flex the contact teeth of one of the first mentioned group of lines into engagement with the contact teeth of one of the second mentioned group of lines.

13. In a telephone exchange, a group of lines, terminal strips in which said lines terminate, said strips being insulatively mounted side by side in a stationary panel, a second group of lines, sets of terminal strips in which said second group of lines respectively terminate, each of said second mentioned sets of strips being independently but fixedly mounted at substantially right angles to said first mentioned strips, sets of flexible contact teeth projecting from said first mentioned sets of strips, one set being

provided for each line of the second mentioned group, sets of contact teeth projecting from said second mentioned sets of strips, each set of strips having as many sets of contacts as there are lines in the first group of lines, and means for flexing a set of contact teeth of any line of the first group, whereby they may be caused to engage the contact teeth of any line of the second group.

14. In a telephone exchange, a group of lines, sets of metallic strips in which said lines terminate, said strips being insulatively mounted side by side in a stationary panel, a second group of lines, sets of terminal strips in which said second group of lines respectively terminate, each of said second set of strips being independently mounted, flexible contact teeth projecting from each of said first mentioned strips, there being as many sets of teeth for each set of strips as there are lines in the second group, contact teeth projecting from said second sets of strips, there being as many sets of teeth for each set of strips as there are lines in the first mentioned group, a plurality of sets of bars, and means whereby the successive displacement of a bar of each set will connect any line of the first mentioned group to a line of the second mentioned group through their respective contact teeth.

In witness whereof, I hereunto subscribe my name this 13th day of December, A. D., 1913.

JOHN NEWBERRY REYNOLDS.
